(57) **CLAIM**

I claim the ornamental design for a part of a parasol, as shown and described.

DESCRIPTION

1. Part of a parasol
- 1.1 is front view of a part of a parasol showing the new design;
- 1.2 is a back view thereof;
- 1.3 is a left side view thereof;
- 1.4 is a right side view thereof;
- 1.5 is a top view thereof;
- 1.6 is a bottom view thereof; and
- 1.7 is a perspective view thereof.
